(57) **CLAIM**

The ornamental design for a fitness rack, as shown and described.

DESCRIPTION

FIG. 1 is a perspective view of the design of this invention;

FIG. 2 is a front view;

FIG. 3 is a rear view;

FIG. 4 is a side view;

FIG. 5 is a top view thereof; and,

FIG. 6 is a bottom view thereof.

1 Claim, 5 Drawing Sheets

FIG. 1

FIG. 2

FIG. 3

FIG. 4

FIG. 5

FIG. 6
